FABRIC CLEANSER

Charles B. Preacher, Sumter, S. C.

Application December 16, 1937, Serial No. 180,127

2 Claims. (Cl. 68—187)

This invention relates to a fabric cleanser and has more particular reference to a device for cleaning clothes or other fabrics wherein a cleaning fluid is caused by heat treatment to circulate 5 from a heating chamber, through the clothes or fabrics to be cleaned, and back into the heating chamber.

An object of the invention is the provision of a novel and an improved fabric cleanser. 10 Another object of the invention is the provision of a generally simplified fabric cleanser wherein the cleaning fluid due to expansion by heat treatment is discharged with considerable force against the fabric to be cleaned and is 15 caused to percolate through the same.

A further object of the invention is to provide such a cleanser wherein agitation of the fabric to be cleaned is not only unnecessary but wherein the fabric is held in such a position that it 20 effectively separates without sealing the cleaning fluid in the heating chamber from the cleaning fluid discharged therefrom whereby efficient circulation is obtained for cleaning the fabric.

Another object of the invention is the provision of such a cleanser having adjustable fabric holding means for adapting it to accommodate various amounts of fabrics to be cleaned. 25

Other objects of the invention include the novel combinations and arrangements of parts as 30 herein disclosed in connection with an embodiment exemplifying the invention and as set forth in the appended claims.

In the accompanying one sheet of drawings:

Fig. 1 illustrates an upright cross section 35 through a fabric cleanser embodying the features of the invention with parts broken away or otherwise removed for the sake of clarity and with a suitable source of heat shown more or less diagrammatically;

Fig. 2 is a fragmentary upright cross section 40 through the cleanser shown in Fig. 1 but taken substantially at ninety degrees therefrom to illustrate the adjustable feature of the fabric holding means; and

Fig. 3 is a plan view of the embodiment of the 45 fabric cleanser chosen to illustrate the features of the invention.

Illustrative of a fabric cleanser for accomplishing the objects of the invention, the drawing shows a container 11 of any suitable shape and construction having a bottom 12, upstanding side walls 13 and an open upper end 15. A heating chamber 16 is provided in the lower end of the container 11 with means for supporting articles 17 of clothing or other fabrics to be

cleaned in spaced relation from the bottom 12 of the container.

The supporting means just mentioned as illustrated in Fig. 1 is constructed of a hollow tubular member 18 receivable within the container 11, resting on the bottom 12 adjacent the side walls 13 and having suitably secured on its upper end above and spaced from the bottom 12 a screen or other perforate member 19 of sufficient strength to support the articles 11 above 10 the chamber 16 and of sufficient porosity as not to interfere with the circulation of the cleaning fluid. The supporting means just described is suitably secured as by, for example, soldering or brazing in place in the lower end of the container 15 and cooperates with adjustable clothes or fabric holding means for so holding various kinds of clothes or fabrics above the chamber 16 that the clothes or fabrics while effectively separating without sealing the cleaning fluid in the chamber 20 16 from cleaning fluid on the clothes or fabrics 17 will nevertheless permit the fluid to percolate downwardly into the heating chamber 16.

As illustrated in Figs. 1, 2 and 3, a suitable adjustable clothes holding means is fabricated 25 by securing a hollow tubular member 21 carrying across its lower end a screen or other member 22 like the member 19 to the lower ends of depending arms 23 which are integral at their respective upper ends with a connecting member 30 24 which is useful as a handle in positioning the adjustable fabric holding means in cooperative relationship with the fabrics to be cleaned in the container 11. The arms 23 and the connecting member 24 constitute a substantially inverted U-shaped member which carries the member 22 for engaging on the clothes or fabrics 17 in the container 11 and for pressing the clothes or fabrics against the member 19 whereby they are squeezed laterally outwardly into close engagement with 40 the side walls 13 of the container.

The depending arms 23 are provided with a plurality of respectively aligned apertures 25 which are spaced longitudinally of each arm and which cooperate with aligned apertures 26 in lugs 45 or ears 27 at the upper ends of diametrically opposite sides of the container and a retaining rod or pin 28 adapted to be inserted through the apertures 26 and any pair of aligned apertures 25 in the arms 23 for adjustably securing the adjustable clothes or fabric holding means in adjusted position.

For conducting the cleaning fluid expanded by the heat from the source shown diagrammatically at 29 in Fig. 1 from the chamber 16 and

directing it over and against the upper surface of the compressed clothes or fabrics 17 in the container 11, a tube or other suitable conduit 31 is secured at one end in an aperture 32 in the 5 lower end of a side wall 13 and aligned with an aperture 33 in the tubular member 18 communicating with the chamber 16. The tube 31 extends outwardly from the aperture 32 and then upwardly along the side of the container 11, inwardly at the upper end of the container 11 and is provided at its upper end with a downwardly directed nozzle or outlet member 34 adapted to direct the expanded fluid on and over the upper surface of the clothes or fabrics 17 as shown in 10 15 Figs. 1, 2 and 3.

In operation, the clothes or fabrics to be cleaned are arranged in the container 11 on the screen member 19. By tilting the tubular member 21 and the screen member 22 to cause 20 it to clear the outlet member 34, the adjustable fabric holding means may be inserted in the open upper end of the container 11 and moved therein to bring the screen member 22 into engagement with the upper surface of the clothes 25 or fabrics to be cleaned. By means of the member 24, the fabric holding means is then manipulated for gently compressing the fabrics between the screen members 19 and 22 and squeezing or spreading them outwardly against 30 the upright walls 13 of the container 11 whereupon the retaining rod 28 is inserted through the aperture 26 in one of the lugs 27 and moved transversely over the top of the container through 35 a pair of the aligned apertures 25 in the arms 23 and the aperture 26 in the other lug 27 for removably retaining the fabric holding means in its adjusted position, the particular pair of aligned apertures 25 depending upon the amount of clothes in the container 11.

40 There are many well known cleaning fluids which are available and suitable for use in the novel fabric cleanser of the invention. For example, I may start with saponified water which may be introduced into the container before or 45 after the clothes or fabrics have been arranged therein as just described above and, by applying heat from the source 29, cause the expansion and consequent circulation of the cleaning fluid from the chamber 16, upwardly through 50 the conduit 31, downwardly out of the outlet member 34 on the upper surface of the fabrics, through the fabrics and back into the chamber 16. The preferred procedure, however, is to supply substantially boiling saponified water to 55 the container 11 after the fabrics have been arranged therein as already described and thus expedite the above described circulatory action for cleaning the fabrics. I have observed that where the substantially boiling water is supplied to the container after the fabrics have 60 been arranged therein, the circulation begins almost immediately and water or vapor is sprayed through the outlet member 34 on the upper surface of the fabrics to be cleaned.

65 It will be noted that the fabrics themselves are employed to resist the upward force of expansion, within the container 11 so that the force resulting from the expansion of the fluid in the chamber 16 causes the fluid to flow through 70 the conduit 31 and the outlet member 34 and to impinge with considerable force against the upper surface of the fabrics. As the fluid is thus displaced from the chamber 16, it is replenished by fluid which has been filtered, percolated or 75 otherwise forced through the fabrics whereby

the fabrics are effectively cleaned. Thus, with novel and inexpensive apparatus, clothes or other fabrics are effectively and quickly cleansed and due to the temperatures where saponified water is employed in the apparatus, the fabrics are likewise sterilized.

While I have described a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A fabric cleaning device comprising a cylindrical container having a closed bottom and an open top and provided with side wall portions extending above the upper margin of said top on opposite sides thereof, said side wall portions having aligned apertures therein, a perforated fabric supporting bottom member spaced from the closed bottom of said container and providing a boiling and pressure chamber therebetween, a perforated fabric compressing member freely slideable within said container to engage fabrics to be cleaned and to press them against said bottom member, said compressing member having a pair of vertical operating arms at opposite sides thereof of a length substantially equal to the height of the side walls of said container, said operating arms having a horizontal handle portion connecting their outer ends outside of said container and each having between its inner and outer ends a vertical series of apertures respectively aligned with the apertures in the other to provide a plurality of pairs of apertures in said operating arms, each pair of apertures being arranged to register with the aligned apertures in the upwardly extending side wall portions of said container, a rod of greater length than the diameter of the container extending through the apertures in the side wall portions of said container and any pair of aligned apertures in said operating arms whereby to fix said compression member adjustably in said container relative to the closed and open ends thereof, and a fluid conducting conduit extending exteriorly of said container and at one end of said conduit communicating with the pressure chamber and at the other end of said conduit communicating with the open end of said container whereby a circulation of a cleaning fluid may be maintained from said pressure chamber into the upper portion of said container for circulation downwardly therethrough.

2. A fabric cleaning device comprising a container having side walls, an open top and a closed bottom, said side walls including oppositely disposed portions extending above said open top and having aligned apertures therein, a fabric supporting perforate screen in said container, means for spacing said screen from the closed bottom of said container to provide a boiling and pressure chamber between said screen and said closed bottom, a fabric compressing perforate screen freely slideable within said container to press fabrics to be cleaned against said fabric supporting screen, a pair of vertical screen supporting arms at opposite sides of said fabric compressing screen and extending outside of said container through the open top thereof, said screen supporting arms having a horizontal handle member connecting their outer ends outside

of said container and each said screen supporting arm between its outer and inner ends being provided with a vertical series of apertures horizontally aligned with those in the other screen supporting arm respectively to provide a plurality of pairs of horizontally aligned apertures in said arms, a rod of greater length than the diameter of said container removably insertable through the aligned apertures in said side wall portions and any pair of aligned apertures in said screen supporting arms for releasably and adjustably securing said fabric compressing screen within said container relative to the closed and open ends thereof, and a fluid conduct-

ing conduit communicating at one end with the pressure chamber, extending therefrom exteriorly of said container and at its other end extending into the open top of said container, whereby a circulation of cleaning fluid is maintainable from said pressure chamber to the upper portion of said container, said fluid conducting conduit having outlet means at its upper end for spraying the circulating cleaning fluid downwardly against the upper surface of the fabrics to be cleaned for circulation downwardly there-through.

CHARLES B. PREACHER.
